UNITED STATES PATENT OFFICE.

JAMES AUSTIN, OF DETROIT, MICHIGAN.

TILE OR BLOCK FOR FINISHING INSIDE WALLS.

SPECIFICATION forming part of Letters Patent No. 292,887, dated February 5, 1884.

Application filed August 1, 1883. (No model.)

To all whom it may concern:

Be it known that I, JAMES AUSTIN, of Detroit, in the county of Wayne and State of Michigan, have invented new and useful Improvements in Tiles or Blocks for Finishing Inside Walls; and I do hereby declare that the following is a full, clear, and exact description thereof, reference being had to the accompanying drawings, which form a part of this specification.

This invention relates to certain new and useful improvements in finishing rooms without the necessity of lathing and plastering, and of putting in inside partitions without studding, sheathing, or lathing and plastering, whereby all the effect of hollow walls may be obtained, with proper means of ventilation.

The invention consists in the peculiar construction of proper tiles, and in the method of laying the same and securing the same together and to the walls of the building, as more fully hereinafter described.

Figure 1 is a section in perspective, showing a section of one side of a room finished upon a brick wall, and a section of the other side of a room formed by a partition dividing it from another room. Fig. 2 is a perspective of the rear side of one of my tiles to be applied to the inner side of the outer wall of the building. Fig. 3 is a vertical longitudinal central section through one of the division-wall tiles.

In the accompanying drawings, which form a part of this specification, A represents a tile with a smooth outer face, and provided upon its rear face with a recess, a, in order to lighten the weight of the tile. The tile is formed in a suitable mold under pressure, and its outer face is made of calcined plaster, with a filling within the outer face of a mixture of calcined plaster and sand, sawdust, or any other suitable material, whereby a large saving in the cost of the calcined plaster is effected. Projecting from two edges of this tile are lugs b, and in the opposite edges are recesses c c', adapted to receive the lugs upon the adjacent tile when put in place. The recesses c' are cut through to the rear side, as shown, so that when put in place in front of the brick wall they will allow the ends of the metal binding-strips d, which project from such brick wall, to lie in them, by which

means a hollow space between the wall and tiles is preserved. In laying these tiles in the successive tiers a small quantity of thin putty of calcined plaster is applied to the exposed edges before the next tier is laid, which, in hardening, makes the whole a solid wall, and a small quantity of calcined-plaster putty is placed in the recesses c after they are engaged with the binding-strips, before the next succeeding series above is put in place, which prevents, when such plaster becomes hardened, the binding-strips from becoming loosened.

D represents the tiles designed to be used in the building of partitions, and these are made of the same material and in the same manner as already described, but with channels e through them vertically, both front and rear faces being smooth. These tiles are laid in the same manner as already described, and in such manner that the vertical channels in one tier will be coincident with the channels in the next vertical adjoining tier. These tiles D may have one or more openings, f, in such portions of the wall as is preferred, for ventilating or heating purposes, such openings communicating with the vertical channels through the blocks. After the room has been finished with these blocks or tiles, the walls are rubbed down in any of the known ways to smooth and polish them.

It will readily be seen that in molding these tiles any desired style of ornamentation may be molded in their outer faces, preferably such as will not prevent or interfere with rubbing and polishing them after they are in place, so that a highly-ornamental wall can be furnished with very little comparative expense, without furring out from the outside walls, without studding, lathing, or plastering, and without the liability of cracking and becoming defaced, which generally attend walls made in the usual way, while they are vermin-proof, and will make a building warm or more easily heated than when constructed in the usual way.

I do not claim, broadly, the idea of making building-blocks of plastic material with recesses to receive projections on adjacent blocks, as I am aware that such blocks have been used before.

What I claim as my invention is—

1. A block for inside walls, formed of cheap

plastic material, with an outer facing of calcined plaster, substantially as herein described.

2. A block for inside walls, formed of cheap plastic material faced with calcined plaster, and provided with projecting lugs and recesses, substantially as and for the purpose specified.

3. The block A, formed of plastic material, provided with lugs *b b* and recesses *c c* and *c' c'*, to the latter opening into the rear face of the blocks to receive the binding-strips *d* in addi-

tion to the lug on the adjacent tile, substantially as described.

4. The block D, formed of cheap plastic material faced on both sides with calcined plaster, with vertical channels *e*, lugs *b*, and recesses *c*, substantially as and for the purposes specified.

JAMES AUSTIN.
